ELECTRICAL CONTROL CIRCUITS

Thomas Philip Robinson and Bertram Walter Glover, London, England, assignors to International Standard Electric Corporation, New York, N. Y.

Application February 25, 1954, Serial No. 412,594

Claims priority, application Great Britain February 27, 1953

6 Claims. (Cl. 183—7)

This invention relates to controlling equipment for the supply of electrical power to a load circuit, with particular reference to protective arrangements therefor.

According to the invention, there is provided equipment for protecting an electrical circuit against sustained overloads without the necessity for breaking the circuit, which comprises a relay responsive to load voltage and a relay responsive to load current so arranged that when the load voltage is lower than a predetermined value and the load current is higher than a predetermined value, means are brought into use which reduce the voltage applied to the load.

The invention will be described with reference to the accompanying drawing which illustrates a preferred embodiment comprising a flash-over protection circuit for an electrical precipitator equipment. Such an equipment is fully described in British patent specification No. 684,024 (Air Preheater Corporation).

In the drawing in the interest of simplifying the circuit a convention is used which is now common in electrical circuits and more particularly, telephone switching system circuits. The relay windings are indicated by a reference and a sub-numeral which represents the number of contact sets controlled by the relay. The contacts controlled by the respective relays are not shown adjacent the relay windings but are placed in such a position on the drawing that numerous cross-over points in the circuit are avoided but the contacts are identified with their relays by the use of related references, for example, the reference

RE3

4

indicates that the relay RE3 has four sets of contacts, these contacts being given the references RE3.1, RE3.2, RE3.3, RE3.4 respectively. Similarly, the reference

RE2

1

indicates that the relay RE2 has one contact set which is given the reference RE2.1 in the drawing. Make contacts are indicated by an open triangle and break contacts by a blacked-in triangle.

In a single figure of the accompanying drawing, which is shown on two sheets representing a complete circuit diagram of the precipitator and its controls the main supply circuit to the precipitator consists of saturable reactors LS1—LS6 in series in pairs in each phase of a 3-phase supply to a rectifier (MR1) feeding a load, in this instance an electrostatic precipitator, and further saturable reactors LP1—LP6 connected in permutation across the lines feeding the rectifier and following the series reactors in the circuit.

A step up transformer T1 is normally employed to provide a suitable high voltage to feed the rectifier, and the first saturable reactors LS1—6 may then be connected in series with the primary and the second saturable re-

2

actors LP1—6 in parallel with the primary of this transformer.

These series and shunt saturable reactors are normally employed to obtain control of the D. C. output from the rectifier by means of variations in the magnitude of saturating current applied to auxiliary windings of the reactors. The series reactors LS1—LS6 are adapted to be energized from an A. C. source via transformer T2 and rectifier MR2 whilst the parallel reactors LP1—LP6 are adapted to be energized from the same source via transformer T3 and rectifier MR3. This type of supply circuit is well known.

The present invention provides means for ensuring quick suppression of flash-overs occurring in a precipitator in the following manner.

When the precipitator is working normally and ionisation is taking place, the D. C. voltage and current stand at their normal values. When the rectifier output voltage is reduced, as, for instance, for cleaning of the precipitator, the D. C. voltage is reduced to a value below ionisation level and the current is sensibly zero. These two sets of conditions are normal to the operation of the precipitator and the protective device is not required to function. When a flash-over occurs in the precipitator, however, the impedance of the load circuit is reduced and the load current is mainly limited by the impedance of the series saturable reactors LS1—6, the transformer T1 (if present) and the rectifier MR1. The current in the precipitator rises to a high value and the voltage across the precipitator falls to a low value, but the arc is maintained. These changes in magnitude of D. C. voltage and current are then made to operate the protective circuit by the independent operation of a voltage sensitive relay

RE2

1

and a current sensitive relay

RE1

2

The current sensitive relay

RE1

2

is connected in series with, or across a resistor R1 in series with, the earthed pole of the rectifier MR1 D. C. output and will operate at any normal load current or higher value of current.

The voltage sensitive relay

RE2

1

is connected in the anode circuit of a cold cathode relay tube CC. This tube is supplied with anode voltage from the A. C. source via transformer T5 and rectifier MR5 and is arranged to be triggered by a voltage obtained from the A. C. source via transformer T4 and an auxiliary rectifier MR4 which is connected to the grid of the tube. In reverse series with this grid supply is the voltage developed across resistor R2 which is proportional to the voltage applied to the precipitator. This voltage may be derived from a resistor in series with the HV D. C. voltmeter V as shown in the figure or from a separate potential-divider resistor. When the voltage applied to the precipitator falls to a low value (as it does on flash-over) the voltage across R2, being connected in reverse sense to the grid voltage from MR4, permits the grid voltage to become sufficiently positive with respect

to the cathode to fire the tube. Anode current then flows from rectifier MR5 through relay

RE2

1

contact RE1.2 being then closed.

Relay contacts RE1.2, RE4.3 and RE3.2 are connected into the anode circuit for the following reasons: RE1.2 prevents ignition of the tube CC when starting up, i. e. when the increasing D. C. voltage is approaching ionisation level but before there is any current flow in the precipitator; RE3.2 extinguishes the tube CC as soon as relay

RE3

4

is closed, and permits relay

RE2

1

to release, and in particular opens contact RE2.1, and RE4.3 prevents the completion of the anode circuit until the timing circuit relay

RE4

3

is de-energised.

When both voltage and current relays are closed, their contacts in series will permit relay

RE3

4

and

RE4

3

to become energised from an auxiliary D. C. source as shown in the figure.

The immediate operation of

RE3

4

removes all D. C. saturation from the series saturable reactors in the main circuit by RE3.3 and applies saturation to the parallel saturable reactors in parallel with the transformer primary by RE3.4. The change of impedance in these series and parallel saturable reactors has the effect of transferring the major part of the voltage on the transformer primary to the series saturable reactors with the result that the output voltage from the main rectifier is reduced to a very low value and the arc in the precipitator is extinguished. Condenser C1 becomes charged via resistor R3 and after a predetermined time delay, relay

RE4

3

is operated.

By this time, both the current and voltage relays will be de-energised and contacts RE1.1 and RE2.1 will be open but by-passed by RE3.1 (closed) and RE4.1 (not yet open). Contact RE4.1 now opening will de-ener-

RE3

4

Contact RE4.1 will also disconnect

RE4

3

from the source of supply and as contact RE4.2 will quickly discharge condenser C1, relay

RE4

3

will quickly reset.

The release of

RE3

4

will remove D. C. saturation from the parallel saturable reactors and restore it to the series saturable reactors. The precipitator will thus be restored to normal working conditions.

5 A time delay is necessary between reduction of saturation on the series reactors and increase of saturation on the parallel reactors, on the one hand, and the eventual restoration of normal saturation conditions, on the other, to allow the arc to be extinguished and to prevent hunting of the protective circuit which would otherwise occur owing to the time required for the saturable reactors to assume their new values of impedance and thus extinguish the arc.

10 A suitable choice of time delay in the operation of relay

RE4

3

will enable the flash-over to be suppressed and the precipitator returned to normal operation with a minimum loss of time and precipitation efficiency.

15 It will be seen that arc suppression is effected without a break in the normal supply circuit, and the interruption to normal working may be made as brief as desired by a satisfactory choice of delay times.

20 While the principles of the invention have been described above in connection with specific embodiments, and particular modifications thereof, it is to be clearly understood that this description is made only by way of example and not as a limitation on the scope of the invention.

What we claim is:

1. Equipment for protecting an electrostatic precipitator against sustained flash-overs which comprises: series controlling saturable reactors and shunt controlling saturable reactors; a load-current-sensitive relay and a load-voltage-sensitive relay; a third relay means responsive to the operation of both said relays on the occurrence of normal or greater than normal load current combined with less than normal load voltage to increase the impedances of the said series saturable reactors and to decrease the impedances of the said shunt saturable reactors, whereby the voltage applied to the said precipitator is materially reduced; and a fourth relay means also responsive, after predetermined delay, to the operation of both said relays to de-energise said third relay means and itself, thereby to restore said precipitator and said protection equipment to normal operation.

2. Device for protecting an electrical supply circuit against sustained overloads, comprising first relay means responsive to a load voltage lower than a predetermined value, second relay means responsive to a load current higher than a predetermined value and means controlled by said first and second relay means for reducing the voltage applied to the load on the occurrence of an overload.

3. Device for protecting an electrical supply circuit against sustained overloads, comprising a load-current-sensitive relay, a load-voltage-sensitive relay, a saturable reactor, a main winding for said reactor connected in said supply circuit, an auxiliary winding for said reactor, a source of current for energizing said auxiliary winding, switch means for controlling the connection of said source to said auxiliary winding, and means responsive to the operation of said load-voltage-sensitive and load-current-sensitive relays for actuating said switch means.

4. Device for protecting an electrical supply circuit against sustained overloads according to claim 3, further comprising a time delay circuit and further relay means under the control of said time delay circuit for restoring said reactor to its normal current condition.

5. Device for protecting an electrical supply circuit against sustained overloads, comprising series controlling saturable reactors and shunt controlling saturable reactors, a load-current-sensitive relay and a load-voltage-sensitive relay, a third relay means responsive to the

operation of both said relays on the occurrence of normal or greater than normal load current combined with less than normal load voltage to increase the impedances of the said series saturable reactors and to decrease the impedances of the said shunt saturable reactors, whereby the voltage applied to the said load is materially reduced, and fourth relay means responsive to the operation of both said relays for restoring the impedances of said reactors to their normal values after a predetermined time interval.

6. Device for protecting an electrical supply circuit

against sustained overloads according to claim 5, in which said load-voltage-sensitive relay is connected in the anode circuit of a gas discharge tube arranged to be triggered when the load voltage drops below a predetermined value.
